UNITED STATES PATENT OFFICE.

HENRY STAFFORD HATFIELD, OF HOVE, ENGLAND.

ELECTROLYTIC CELL.

1,001,589.

Specification of Letters Patent. Patented Aug. 22, 1911.

Application filed October 12, 1907. Serial No. 397,060.

To all whom it may concern:

Be it known that I, HENRY STAFFORD HATFIELD, a subject of the King of Great Britain and Ireland, residing at 18 Palmeira Square, 5 Hove, in the county of Sussex, England, have invented certain new and useful Improvements in Electrolytic Cells, of which the following is a specification.

The invention relates, not to electrolytic 10 cells in general, but to cells in which the sole result of the passage of a current is, that some substance is transferred from one part of the cell to another. Such cells I call electrolytic transference cells. They are thus 15 distinguished from other cells in which the result of the passage of a current is to produce permanent changes in the strength or chemical nature of the electrolyte, or to liberate substances from chemical combination, 20 or both.

Electrolytic transference cells need to be distinguished by a name from others, because they have quite special applications and advantages for these applications. The 25 substance transferred from one part of the cell to another may be thereby rendered more pure, as in the case of the copper refining cell. Impure copper serves as anode; only copper, and not impurities, is transferred 30 to the cathode by the action of the current. Again, they are used for measuring purposes, as in the Wright mercury meter. The substance after transference always appears on one electrode; and before my invention, 35 the mass of substance to be transferred formed the other electrode, or a part of it. No other way of feeding the substance into the electrolyte continuously as the deposition took place at the other electrode was known, 40 and hence a number of substances, such as bromine, which are insulators and cannot therefore be used as electrodes, could not by any known means be electrolytically transferred.

45 My invention consists chiefly in the use of an electrolyte, which can dissolve, and is saturated with, an insulating substance to be transferred. Such electrolytes can be formed to suit many substances never hitherto transferred electrolytically. Further in common with all electrolytic transference cells my electrolyte is not permanently altered in composition by the passage of the current; the net and sole result of the latter 50 is to transfer the insulating substance from

one part of the cell to another by rendering it temporarily unsaturated with respect to the insulating substance at one electrode.

As hereinbefore indicated, my invention relates to electrolytic cells of that type in which insulating substances are deposited. Previously to my invention only one instance of this type was known and it differs widely from the cells of my invention. For convenience I group all cells under the type above mentioned into two classes, one of which constitutes my present invention and the other of which embraces the cell previously known. In both classes a compound of the body to be deposited forms a constituent of the electrolyte. This compound is decomposed by the electric current. At one electrode (hereinafter called the first electrode) the body is deposited; at the other electrode (hereinafter called the second electrode) a compound of the body to be deposited is reformed. 60 65 70 75

In the already known class the second electrode is formed of a conducting body capable of dissolving the body to be deposited or uniting with it, and this electrode is placed in contact with a reserve supply of the body to be deposited, so that it may always be saturated therewith. At this electrode, the compound decomposed is reformed, a supply of the body to be deposited being derived from the electrode, and, through the latter, from the reserve supply. It may be said of this known class, that the 80 85 90 second electrode is depolarized by the body to be deposited which is contained in it.

In the class which constitutes my present invention, (hereinafter termed the depolarizing electrolyte class) it is not necessary for the working of the cell that the second electrode should have the power of dissolving the body to be deposited or of uniting with it, and the said electrode need not be in contact with the reserve supply of the body to be deposited. By my invention, the electrolyte is capable of dissolving the body to be deposited and is saturated therewith through being in contact with a reserve supply of the said body. At the second electrode the compound decomposed or one similar to it but containing less of the body to be deposited is reformed, the supply of the body to be deposited being derived not from the second electrode but directly from the electrolyte, and through the latter, from the 100 105 110

reserve supply. In the class which constitutes my present invention, the second electrode is depolarized by the electrolyte.

In expressing the ideas of "solubility" 5 and "saturation" I understand that the electrolyte is of such a nature that the body to be deposited may be withdrawn from it to any extent up to a certain point, without any concomitant evolution or absorption of 10 other elements or compounds taking place, and further, that when the electrolyte has been unsaturated by abstraction of the deposited body, contact with the latter will again saturate it.

15 I may arrange to hermetically seal the cell, and pivot it so that by turning it the deposited body may be returned to the reservoir from which the solution at the second electrode is regenerated. If the body to be deposited be a liquid I may use a self-emptying siphon to measure it and give a multiple dial effect, as employed in the measurement of mercury by Wright, Patent No. 702,844, dated 17th June, 1902. Or I 20 may cause the liquid or gas deposited to flow into a number of tubes so arranged that when one is full the next thereto will receive the liquid or gas.

In order that my invention may be more 30 readily understood, I shall now proceed to describe it with reference to the accompanying sheet of drawings in which,

Figure 1 is an end elevation of the cell constituting a meter as aforesaid; Fig. 2 is a 35 side elevation thereof; and Fig. 3 is a section on the line *a*—*b* of Fig. 1; Fig. 4 shows another house service meter which differs from that shown in Figs. 1, 2 and 3 in that instead of a liquid being deposited a gas is 40 deposited; Fig. 5 shows an electrolytic cell in which the body to be deposited is a solid; Fig. 6 illustrates a case in which a liquid or solid is deposited but in which the electrical resistance of the cell is arranged to 45 be as low as possible; Fig. 7 illustrates a cell designed for the purification of a gas by electro-deposition; and Fig. 8 illustrates a modified form of cell for purifying gas by electro-deposition.

50 Referring now to Figs. 1, 2 and 3, the cell *S* is of glass divided by the partition *H* into two parts. The electrolyte is a dilute solution of hydro-bromic acid saturated with bromin. A pool of bromin *C* lies on the bottom of the cell; in the right hand compartment *E* it is at a higher level and passes into the left hand compartment and keeps the level of the pool there constant through a hole at *F*. The cathode *B*¹ consists of an 55 iridium plate close above the surface of the bromin. The anode *A*¹ is of platinum and is placed in a funnel ending in a reading tube *D* (Figs. 1 and 3) which is formed as a self-emptying siphon. When current is 60 passed between the electrodes *A*¹ (in this

case the positive electrode) and *B*¹ bromin is deposited on *A*¹ and since the solution is already saturated with bromin the latter drops from the electrode *A*¹ into the measuring tube *D*. At the electrode *B*¹ hydro-bromic acid is formed by the combination of the hydrogen (there released) with the bromin dissolved in the electrolyte. The latter then becomes unsaturated with bromin which however dissolves into it again 70 from the pool near the electrode. For use as a house service meter a high resistance *H*¹ is placed in series with the cell having a positive temperature co-efficient of resistance sufficient to compensate the temperature co-efficient of the cell and with this a low resistance *G* is placed in parallel the greater part of the current passing through this low resistance. The cell is pivoted so that it can be inverted to return the bromin 75 to the reservoir after a manner well known in connection with mercury electrolytic meters. The high resistance is constructed partially of a pure metal such as iron having a large positive temperature co-efficient 80 and partially of a suitable resistance alloy such as manganin. The proportion of the two metals is such that the whole circuit shall have an approximately constant resistance with change of temperature. 85

In Fig. 4, I illustrate a meter which differs from that previously described in that it is adapted for the measurement of a gas liberated by the current instead of the measurement of a liquid so liberated. The 100 gas designed to be liberated in the specific case now under description is chlorin so that this gas will be deposited as in the former case at the anode *A*. The electrolyte employed is a solution of ferric chlorid saturated with chlorin of which there is a reserve supply in the space *C*⁴. The chlorin liberated at the anode *A* is collected at the upper part of the depositing tube *D*⁴ which is so constructed as to return upon itself for 105 purposes of easy resetting. The equivalent of the liquid displaced in the depositing tube overflows into the tube *E*⁴. The electrolyte which is converted from ferric to ferrous chlorid at the electrode *B* by the action of the current is reconverted by contact with the chlorin in the space *C*⁴, that is to say by purely chemical action, into ferric chlorid. Measurement may be made of the amount of gas collected in the tube *D*⁴ 110 and or by measurement of the liquid displaced into the tube *E*⁴. A scale such for example as is shown in this figure as well as in Fig. 1 may be employed for the measurement of the deposited body. I have 115 spoken of the gas being liberated in this case at the anode. I do not imply that in other cases the body to be deposited is necessarily liberated at the anode. It will be 120 obvious that the electrode at which the 125

body to be deposited is liberated depends upon the electro-chemical sign of the body.

In Fig. 5 I illustrate a cell in which a solid is to be deposited for example for the purpose of purifying it. A is the first electrode and B the second. C⁵ is a mass of the impure solid in the form of small lumps which keep the liquid around the electrode B saturated. By the opening D⁵ more solid may be introduced as it is dissolved away in the bath. The solid deposited on A may fall of itself into the tube E⁵ but if it does not do so it may be periodically or continuously scraped away from the electrode. As an illustrative case I may mention the purification of sulfur. The electrolyte employed in this case will be a strong solution of sulfid of sodium saturated with sulfur. While these cells exhibit the principles of my invention in its simplest form they have the drawback that the electrodes are comparatively wide apart in order that solution depleted at the second electrode shall reach the first without being resaturated with the substance to be deposited. In the use of such cells for the purification on a commercial scale of substances this would lead to an excessive waste of electric energy in the resistance of the cell. For this purpose I prefer to place the electrodes close together and by suitable means cause a circulation of the liquid away from the first electrode over the second. The electrolyte after passing the second is then brought into contact with substance and saturated, finally returning to its starting position. Two such constructions are figured diagrammatically in Figs. 6 and 7. In Fig. 6 which is suited particularly for purifying a liquid or a solid the two electrodes are placed close together at A and B and a circulation is maintained by a pump D⁶ in the direction shown by the arrows. In the compartment C⁶ the liquid or solid is brought into thorough contact with the substance which is to be dissolved and which lies in a pool or mass at the bottom of the said compartment. The electrodes are pierced with holes to allow of free circulation of liquid through them.

Fig. 7 illustrates a cell which is adapted for electro-deposition of gas by deriving it from a mixture with other gases. The electrolyte is contained in the cell A, B, E⁷, F⁷, the first electrode, on which gas is deposited, being the electrode A, and the second electrode B. The first electrode A is formed in parallel bars on a grating so that the gas which is deposited at its under side can easily escape upward. Electrode B is porous and the liquid gradually percolates through it falling on trays in the absorption chamber C⁷; through this absorption chamber the impure or mixed gas from which the gas to be deposited has to be separated, is passed. The electrolyte on reaching the bottom of

this chamber is restored to the upper part of the cell by a pump at F⁷. At the electrode B the electrolyte becomes unsaturated with respect to the gas to be deposited and in passing down the absorption chamber becomes resaturated therewith. This apparatus will not be efficient as applied to the deposition of a gas such as chlorin, the solubility of which in most electrolytes varies considerably with the pressure. If the cell in Fig. 7 were used for the deposition of chlorin the liquid being saturated with chlorin at atmospheric pressure by contact with the electrode A would lose a certain amount of free chlorin by the action of the electrode B and in passing through the absorption chamber C⁷ in which the gas contains chlorin at a lower partial pressure than the atmospheric would not be resaturated here to the strength corresponding to atmospheric pressure. In Fig. 8 this difficulty is avoided because the gas absorption chamber D is connected with the cell by a long pipe F⁸, the other details being similar to Fig. 7. It is then possible to either increase the pressure in D⁸ above the atmospheric by the amount corresponding to the head of liquid in the pipe F⁸, or to decrease the pressure above the cell at the top of F⁸ by a corresponding amount. The condition to be fulfilled is that the pressure of the pure gas on the liquid near the electrode at which it is given off should be equal to or less than the partial pressure of this gas in the mixed gases in D.

I claim,

1. An electrolytic transference cell consisting of an electrolyte in which any insulating substance deposited by the passage of the current through the cell is soluble and with which it is saturated; two electrodes on one of which the insulating substance is deposited and at the other of which the electrolyte becomes unsaturated with respect to the substance deposited without permanent alteration of the electrolyte; and a supply of the insulating substance deposited resaturating by contact therewith the liquid which has become unsaturated, the sole result being to transfer the insulating substance from one part of the cell to another, substantially as described.

2. An electrolytic transference cell consisting of an electrolyte in which any insulating substance deposited by the passage of the current through the cell is soluble and with which it is saturated; two electrodes on one of which the insulating substance is deposited and at the other of which the electrolyte becomes unsaturated with respect to the substance deposited without permanent alteration of the electrolyte; a supply of the insulating substance deposited resaturating by contact therewith the liquid which has become unsaturated; and a device

for causing the circulation of the electrolyte with reference to the resaturating substance, substantially as described.

3. An electrolytic transference cell consisting of an electrolyte in which any substance deposited by the passage of the current through the cell is soluble; two electrodes on one of which the substance is deposited and at the other of which the electrolyte becomes unsaturated with respect to the substance deposited; an absorption chamber containing a supply of the substance deposited resaturating by contact therewith the liquid which has become unsaturated; and a head of liquid between the electrodes and the absorption chamber so that the pressure on the electrolyte at the electrodes may be lower than that in the absorption chamber, substantially as described.

4. An electrolytic transference cell consisting of an electrolyte in which any substance deposited by the passage of the current through the cell is soluble; two electrodes, one of them being porous and on one of which the substance is deposited and at the other of which the electrolyte becomes unsaturated with respect to the substance deposited; and a supply of the substance deposited resaturating by contact therewith the liquid which has become unsaturated, substantially as described.

In witness whereof I have signed my name to this specification in the presence of two subscribing witnesses.

H. STAFFORD HATFIELD.
